FOUNDRY FLASK

Harold Sidney Garrett, Normandy, Mo., assignor
to Wagner Electric Corporation, St. Louis, Mo.,
a corporation of Delaware

Application July 31, 1939, Serial No. 287,509

3 Claims. (Cl. 22—110)

My invention relates to a foundry flask and particularly to means for securing accurate and permanent alignment between the cope and the drag. Heretofore great difficulty has been encountered in maintaining such alignment between the parts of the flask due to the fact that such parts are made of relatively soft and light material, such as aluminum, which is subject to rapid wear from the jars to which the flask is subjected during the molding operation.

One object of my invention is to provide aligning means for the cope and drag of a foundry flask which is so constructed that it will withstand the rough usage, to which it is necessarily subjected, with but little wear.

A further object of my invention is to provide wear compensating means by which such slight wear as does occur, may be quickly and easily taken up.

20 In the accompanying drawing, which illustrates one form of foundry flask made in accordance with my invention, Figure 1 is a side elevation; Figure 2 is an enlarged fragmentary vertical section; Figure 3 is a section taken on the line 3—3 25 of Figure 2; Figure 4 is a section taken on the line 4—4 of Figure 2; and Figure 5 is a diagrammatic view.

The flask comprises a cope 6, a drag 7, and a match plate 8. The match plate carries one part 30 of a divided pattern 9 on one face and the other part 9' on the opposite face. The cope is provided with a sand strip 10. All the above named parts may be of any usual and well known construction.

35 Carried on the ends of the drag are lugs 11 and on the ends of the cope similar lugs 12. Each of the lugs 11 is provided with a tapered opening 13 for the reception of the enlarged tapered foot 14 of one of the guide pins 15 and 15'. The small 40 ends of the feet 14 terminate some distance back of the faces of the lugs to permit the feet to be drawn into the lugs to take up wear. This is accomplished by means of nuts 16 engaging threaded studs 17 carried by the feet. Lock washers 18 are employed to prevent accidental 45 loosening of the nuts.

Formed in each of the lugs 12 is a tapered opening 19 to receive one of the tapered plugs 20 and 20'. These plugs are alike except that plug 50 20 has a round opening 21 to receive the round guide pin 15, and plug 20 has a slot 22 to receive the non-circular guide 15'. This pin may be of any cross section which will permit of variation in its diameter by rotation. In the drawing I 55 have shown it as hexagonal so as to provide three

diameters A, B and C (Figure 5). In practice, the difference between these diameters is very slight. For example, I find that if diameter A is .749", diameter B may be .75", and diameter C may be .751". Plugs 20 and 20' are held in the lugs by nuts 23 on threaded hubs 24 carried on the plugs. Lock washers 25 are employed and the nuts 23 may be used to take up wear in the same manner as nuts 16. Guide pin 15 passes through a round hole 26 in one end of the match plate 10 and pin 15' passes through a slot 27 in the other end thereof.

By making the feet 14 and plugs 20 and 20' sufficiently large in diameter, it is possible to reduce the wear between these parts and the lugs 15 11 and 12 to a minimum notwithstanding the relatively soft material of which the latter is made and the rough usage to which the device is subjected. I have found in practice that the largest diameter of the foot 14 should be at least .15 20 times the effective length of the pin and that the length of the foot should be at least one-half of its diameter. The plugs 20 and 20' should be at least as large as the feet 14. I make both the guide pins, including their feet and the plugs, of 25 hardened steel and chrome plate the pins to provide a very hard and durable surface.

While I have shown my flask used with a match plate carrying both parts of the divided pattern, it will be understood that it may be used in connection with two match plates each carrying one part of the pattern.

It will be seen that this construction provides rigid and aligning means which is liable to but little wear. Further, such slight wear as may occur, may be easily taken up. Any wear between the feet and the lugs, or between the plugs and the lugs, may be taken up by tightening nuts 16 and 23. Any wear in the slot 22 may be compensated for by turning the pins 15' through the proper angle to bring a larger diameter into effective position.

Having fully described my invention, what I claim as new and desire to secure by Letters Patent of the United States is:

1. A foundry flask comprising a cope and drag, a guide pin carried by one of said parts, said guide pin having an enlarged tapered foot entering a tapered opening in said part, a threaded stud on the end of the foot opposite the pin, a nut on said stud for drawing said foot into said opening to anchor the pin and take up wear, a tapered plug carried by the other part, said plug entering a tapered opening in said latter named part, and means for drawing said plug into its opening to 55

anchor it and take up wear, said pin engaging an opening in said plug to align the cope and drag.

2. A foundry flask comprising a cope and drag, a pair of guide pins carried by one of said parts, said guide pins having enlarged tapered feet entering tapered openings in said part, means for drawing said feet into said openings to anchor the pins and take up wear, a pair of tapered plugs carried by the other part, said plugs entering 5 tapered openings in said latter named part, means for drawing said plugs into said openings to

anchor the plugs and take up wear, one of said plugs being provided with a slot engaging one of the pins.

3. A construction containing the elements combined as defined in claim 2 in which the guide pin engaging the slot in one of the plugs is polygonal in cross section, the polygon comprising two or more sets of opposing faces providing differing diameters whereby wear may be compensated by rotation of the pin. 10

HAROLD SIDNEY GARRETT.
